UNITED STATES PATENT OFFICE.

WILLIAM ALLEN PENFIELD, OF MERIDEN, CONNECTICUT, ASSIGNOR TO THE BRADLEY & HUBBARD MFG. CO., OF MERIDEN, CONNECTICUT, A CORPORATION.

WICK-TUBE FOR CENTRAL-DRAFT LAMPS.

SPECIFICATION forming part of Letters Patent No. 783,798, dated February 28, 1905.

Application filed December 30, 1904. Serial No. 238,895.

To all whom it may concern:

Be it known that I, WILLIAM ALLEN PENFIELD, a citizen of the United States, residing at Meriden, in the county of New Haven and State of Connecticut, have invented a new and useful Improvement in Wick-Tubes for Central-Draft Lamps; and I do hereby declare the following, when taken in connection with the accompanying drawings and the letters of reference marked thereon, to be a full, clear, and exact description of the same, and which said drawings constitute part of this specification, and represent, in—

Figure 1, a side view of a blank from which my improved inner wick-tube is formed; Fig. 2, a side view, partially in section, illustrating one step in the production of my improved tube and showing the same before the tube is longitudinally contracted; Fig. 3, a side view, partially in section, of the finished wick-tube, showing the integral drip-trough.

This invention relates to an improvement in wick-tubes for central-draft lamps, and particularly to such as are provided with so-called "drip-troughs"—that is, provision inside the tube to return any oil which may overflow the upper end of the tube back into the font. In the more general construction of troughs a separate piece is inserted into the tube and secured therein.

The object of this invention is to form the trough in the same piece with the inner wick-tube and as will be more fully hereinafter described, and particularly recited in the claims.

In illustrating my invention I have shown only the inner wick-tube of a central-draft lamp, the invention being applicable to central-draft lamps of various types.

In carrying out my invention I employ a tube 2, in which I form near the top an annular groove 3, forming a corresponding internal shoulder 4, the metal above the groove being turned abruptly inward, forming a short curve 5, while the metal below the groove gradually merges into a main portion, forming a long taper 6. In other words, the curves

above and below the groove are struck on circles having different radii, as clearly shown in Fig. 2. At the time the groove is formed or subsequently a hole 7 is formed in one side of the tube just above the groove. The tube thus grooved and punched is placed in suitable dies and the tube contracted lengthwise, which forces the groove upward or the upper portion of the tube downward, so that the bend in the metal forming the groove 3 extends upward, or, in other words, the curved portion 5 overlaps the inclined surface 6, so as to form an internal trough 8, as shown in Fig. 3. Any oil which may pass over the upper edge of the wick-tube owing to weeping or any other cause will follow down the inner surface of the tube to the trough 8 and escape through the hole 7 into the lamp-font or against the surface of the wick below its upper edge. By a very simple operation, therefore, I am enabled to form a drip-trough inside the inner wick-tube and without inserting additional pieces therein and avoid soldering or other attachments which have heretofore been necessary.

Having fully described my invention, what I claim as new, and desire to secure by Letters Patent, is—

1. An inner wick-tube for central-draft lamps having a drip-trough formed integral with the body portion of said tube and located inside the same, substantially as described.

2. An inner wick-tube for central-draft lamps comprising a tube having an annular groove formed in the outer face thereof, the metal forming said groove extending inwardly and upwardly below the upper end of the tube, portions of the tube above and below said groove arranged in the same plane where-by a drip-trough is formed within the tube and integral therewith, substantially as described.

3. An inner wick-tube for central-draft lamps comprising a tube having an external groove and a corresponding internal shoulder, the metal above the groove turned abruptly

upward, and the metal below the groove gradually tapered downward, said shoulder extending inwardly and upwardly above said abrupt bend, whereby a drip-trough is formed inside 5 the tube and from a single piece of metal, substantially as described.

In testimony whereof I have signed this

specification in the presence of two subscribing witnesses.

WILLIAM ALLEN PENFIELD.
